UNITED STATES PATENT OFFICE.

PERRY D. BLACKDEN, OF EVERETT, MASSACHUSETTS.

WATER-TUBE BOILER.

SPECIFICATION forming part of Letters Patent No. 635,710, dated October 24, 1899.

Application filed May 29, 1899. Serial No. 718,690. (No model.)

To all whom it may concern:

Be it known that I, PERRY D. BLACKDEN, of Everett, county of Middlesex, State of Massachusetts, have invented an Improvement in 5 Water-Tube Boilers, of which the following description, in connection with the accompanying drawings, is a specification, like letters on the drawings representing like parts.

This invention has for its object the production of a very efficient, strong, and simple water-tube boiler having a very large heating-surface relative to its size, whereby steam may be very quickly generated and readily maintained at high pressure. Means are also 15 provided for superheating the steam.

Owing to its economy of space, safety, rapidity of steaming, and simplicity of construction the boiler embodying my invention is particularly adapted for use in connection 20 with motor-vehicles, yachts, &c., although its use is in no manner restricted thereto.

Figure 1 is a vertical sectional view of a water-tube boiler, illustrating one embodiment of my invention. Fig. 2 is a transverse 25 sectional view on the line 2 2, Fig. 1, looking down; and Fig. 3 is an enlarged sectional detail to be described.

The main portion of the boiler is inclosed in a suitable metallic shell A, herein shown 30 as rectangular in shape and braced at the vertical and upper corners by suitable angle-irons a, riveted thereto. Within this shell I mount the boiler proper, it comprising a steam chamber or dome B, water-chamber C, and 35 water circulatory tubes D, connected with the inner heads b and c of said chambers, the ends of the tubes being expanded at d^x in holes in the heads by means of any suitable tube-expander. The heads b and b' of the 40 steam-chamber are connected by a suitably-shaped and flanged ring b^x, which forms the side walls of the chamber, a steam-pipe b^s leading from the chamber through the shell A to the throttle, (not shown,) and the heads, 45 while equidistant from each other at all points, are preferably dished, as shown in Fig. 1.

Inner and outer forged rings c² and c^x are riveted between the heads c and c' of the water-chamber C to form a ring-like or annular 50 chamber with a central opening C', the heads being also slightly dished, as shown in Fig. 1. As the dishing of the heads of the two

chambers is made the same, the two parts of each at one side of the median line will be in parallelism.

The water-chamber is preferably made rather shallow in order to present a rather thin body of water to the action of the heating medium, the water-chamber, as herein shown, forming the top of the combustion-chamber A^x of the shell, which I have shown herein as provided with any suitable burners M for a hydrocarbon fuel, though my invention is not restricted thereto.

The water-chamber is supported in the shell 65 in any suitable manner, as by making notches a^x in the angle-irons to receive the edges of the chamber.

By providing a central opening in the water-chamber the heated products from the 70 combustion-chamber pass freely into the space between the water and steam chambers, circulating around and heating the water-tubes D exteriorly and finally passing from the shell through an opening A² into a flue A³. 75

Referring to Fig. 2, the opening C' is shown as elongated and the water-tubes are arranged in two sections, one at each side thereof, at right angles to the heads b and c, but inclined toward each other, owing to the dishing of the 80 heads, the tubes serving also to brace the heads without other devices. Heating-flues H are extended through the water-tubes and the water and steam chambers and are rigidly secured to the outer heads b' and c' of 85 the latter by means of screw-plugs h', screwed tightly into holes in the outer heads, the ends of the flues being expanded, as at h^x, Fig. 3, in the plugs. The plugs are provided with polygonal heads h², by which they are screwed 90 into place or removed, the holes for the plugs being made large enough to admit an expanding device to operate on the opposite water-tube. By this construction repairs can be 95 readily made, such as the removal of a damaged water-tube and the substitution of a new one, without requiring the removal of a section of tubing, as it is only necessary to remove the corresponding heating-flues H. The latter convey the heat from the combustion-chamber to the interior of the column-like 100 bodies of water passing through the water-tubes, thus greatly increasing the effective heating-surface of the boiler. Any portion

of the heating-flues exposed above the water-level in the steam-chamber B will act to superheat the contents of said chamber. The flues serve also as braces for the outer heads 5 *b'* and *c'* of the chambers B and C, obviating the use of additional tie-rods and braces and making a very strong, rigid, yet light construction.

In Fig. 1 the arrows show the passage of 10 the heated products from the combustion-chamber.

Steam is rapidly made and readily maintained at the required degree of pressure, the 15 heating-surface is very great relative to the size of the boiler, and the construction described reduces the danger from an explosion to a minimum.

Having fully described my invention, what 20 I claim, and desire to secure by Letters Patent, is—

1. In a water-tube boiler, a shallow water-chamber composed of upper and lower heads dished and in parallelism at each side of the 25 central opening of the chamber, and inner and outer rings connecting them, to form a central, elongated opening, a steam-chamber composed of top and bottom heads dished, and a ring connecting them and forming the side walls of the chamber, said chamber being 30 of greater depth than the water-chamber, and connections between said chambers to effect circulation of the water in hollow columnar form, heated on their inner and outer surfaces.

2. A water-tube boiler, comprising a shallow, annular water-chamber, a steam-chamber having a greater depth than the water-chamber, water-tubes connecting said chambers, and heating-flues passing through the 35 said tubes and chambers and secured to the outer heads of the latter, the heads of the chambers being dished and in parallelism at each side of the central opening of the water-chamber.

3. In a water-tube boiler, an inclosing shell 45 having a combustion-chamber in its lower portion, a shallow, rectangular water-chamber therein having an elongated central opening, a rectangular steam-chamber in the upper part of the shell and of greater depth than 50 the water-chamber, water circulatory tubes connecting said water and steam chambers, and heating-flues extended from the outer head of one to the outer head of the other of said chambers through the water-tubes, the 55 said flues serving also to superheat the contents of the steam-chamber, the tubes and flues being arranged in two groups separated at their lower ends and located at opposite sides of the central opening of the water-chamber.

In testimony whereof I have signed my name to this specification in the presence of two subscribing witnesses.

PERRY D. BLACKDEN.
